UNITED STATES PATENT OFFICE.

EDGAR L. LOGEE, OF PROVIDENCE, RHODE ISLAND.

DESIGN FOR A LACE-PIN.

SPECIFICATION forming part of Design No. 16,770, dated July 6, 1886.

Application filed April 13, 1886. Serial No. 198,577. Term of patent 3½ years.

To all whom it may concern:

Be it known that I, EDGAR L. LOGEE, a citizen of the United States, residing at Providence, in the county of Providence and State 5 of Rhode Island, have invented and produced a new and original Design for Jewelry, the same consisting of a Lace-Pin, of which the following is a specification, reference being had to the accompanying drawings, forming a part 10 thereof.

Figure 1 is an elevation or face view of my said newly-designed lace-pin, and Fig. 2 is a side or edge view of the same, these two figures being necessary to fully illustrate the 15 design.

The leading feature of my design is a representation of a conventionalized spray or stalk of grain ornamented with grooves, with parallel sides on the head and stalk. A jewel-

setting is combined with the spray, and also 20 with a straight bar and a pair of scrolls.

In the drawings, *a a* represents a curved spray or stalk of grain with parallel-sided grooves on the head and stalk; *b*, a straight chord or bar; *c*, a jewel-setting; *d d*, two 25 scrolls, and *e* a hinged pin. One of the scrolls and the lower side of the setting have depending a number of ornamental balls.

I claim—

The design for a lace-pin, consisting of a representation of a conventionalized curved spray, 30 *a*, a straight chord, *b*, a jewel-setting, *c*, and the scrolls *d*, substantially as herein illustrated and described.

EDGAR L. LOGEE.
